UNITED STATES PATENT OFFICE

DEEW HEAD, OF CHICAGO, ILLINOIS

AIR-CONDITIONING DEVICE FOR INTERNAL-COMBUSTION MOTORS

Application filed December 12, 1927. Serial No. 239,407.

This invention relates to improvements in air conditioning devices for internal combustion motors, and more particularly to a device for treating the air entering the carburetor of the motor and to thereby improve the operating conditions.

The object of the invention is to provide a practical and dependable apparatus through which the air is drawn prior to delivery to the carburetor, and by a novel application of the cooling water of the motor to obtain a more complete cleansing action.

A further object of the invention is to provide a practical means for bypassing a portion of the water from the cooling system, maintaining a constant circulation of this water through the apparatus, and finally controlling the circulation to prevent overflow and consequent depletion of the cooling water. A somewhat similar apparatus is disclosed in my previous application, Serial No. 158,448, filed January 3, 1927, and hence the present disclosure is directed to certain improved features of construction and arrangement, the preferred embodiment thereof being illustrated in the accompanying drawings, in which

Figure 1 is a general view in side elevation of an automobile motor and radiator, showing the complete installation of the air conditioning device.

Figure 2 is an enlarged detail view in vertical section through the air treating casing.

Figure 3 is a cross-sectional view taken on line 3—3 of Figure 2.

Figure 4 is a cross-sectional view taken on line 4—4 of Figure 2; and

Figure 5 is an enlarged detail view in section of the so-called siphon breaker in the water line.

In Figure 1 is shown a typical motor assembly for an automobile consisting of the motor 1, provided with a carburetor 2, a belt-driven fan 3, and a radiator 4 located in front of the motor. The radiator performs its usual function of cooling the water, being connected at top and bottom with the water jacket of the motor. The water circulating pump 5 for the cooling system is located intermediate the lower water connection (not

shown) and the motor. Further details of motor construction and operation are omitted, as these are matters of general knowledge and practice.

The main part of the air conditioning apparatus is a cylindric casing or housing 6 mounted just below and forwardly of the carburetor 2, a suitable bracket or supporting arms 6^a, 6^b being riveted to the casing and adapted to be bolted or otherwise fastened to the motor block (Figure 4). The casing is mounted in a vertical position and is connected with the air intake of the carburetor by an elbow 7 of slightly greater diameter at its outer or lower end. As clearly shown in Figure 2, the casing comprises an outer cylindric shell 8 and an inner concentric shell 9^a. The outer shell is preferably made in two sections parted midway between its ends, and joined together with a lap joint as at 10, so that the same can be taken apart for cleaning and assembly, but in use it can be considered as a unitary casing. The upper end of the outer shell 8 is partially closed by a top wall 11 having a centrally located opening 12 of 75 relatively large diameter surrounded by a flange 11^a over which fits the lower end of the elbow 7. At the lower end of the casing is a conical shaped bottom wall 13 forming a relatively shallow basin or sump with its 80 deepest point at the center.

The inner shell 9 has the form of an inverted cylindric receptacle opening downwardly and closed at the upper end by a wall 9^a. The diameter of the inner shell 9 is slightly more than one-half the diameter of the outer shell 8, thus forming an annular space between, and so proportioned that its area is substantially the same as the cross-sectional area of the inner shell. The upper 90 wall 9^a of the inner shell 9 is spaced below the top wall 11 of the outer shell 8 a distance substantially equal to the radial distance between the two shells, and at its lower end said inner shell is spaced a somewhat greater 95 distance above the bottom wall 13. Around the upper end of the inner shell 9 is a plurality of radial tubes 14, shown in Figure 3 as five in number, spaced equidistantly apart around the circumference. These tubes 100

register with circular holes in the outer casing and communicate with the atmosphere.

Extending through the outer cylindric shell 8 is a water inlet connection 15 in the 5 form of a fitting inserted through a hole in the shell a short distance above the bottom wall. At the inner end of this fitting is a downwardly curved or bent pipe 16 terminating at its end near the center of the casing. 10 The outer end of the fitting is connected with a supply pipe 17 leading forwardly and upwardly and forms a part of the circulating system presently to be described. Also leading through the outer shell is a somewhat 15 similar fitting 18, this fitting being preferably located 90° away from the first-mentioned fitting and entering at a slightly lower level. A pipe 19 extending radially inward from the fitting 18 to the center of the casing 20 and curving downwardly, terminates just above the central and deepest point of the conical bottom wall 13. Connected with the outer end of the fitting 19 is a discharge or 25 return pipe 20 leading forwardly toward the radiator.

Referring to Figure 1, the water connections to and from the casing 6 will now be explained: By preference, the liquid supply to the casing 6 is taken off at the top of the 30 water pump 5 at some point 21, although a connection may be made at any desirable point in the cooling system fairly well below the top level. From the point of connection 21, a pipe 22 extends vertically upward to 35 a device termed a siphon breaker 23 mounted just rearwardly of the radiator and as close to the high water level therein as possible. In general, the siphon breaker has the form of an inverted U-tube or fitting, one branch 40 being connected with the pipe 22 and the other with the pipe 17 extending to the water inlet fitting 15 of the casing 6.

For the present it may be assumed that the water from the cooling system is delivered 45 into the basin or sump at the bottom of the outer shell 8 through the pipe line just described, and is discharged through the fitting 18 and return pipe 20 which leads directly to a pump 24 mounted at the forward 50 end of the motor and driven therefrom through a suitable drive. This pump 24 is a separate unit and is operated independently of the main water pump 5 of the cooling system. From the pump 24 is another 55 pipe 25 leading upwardly and discharging into the top of the radiator.

Referring to the siphon breaker 23, the same comprises an inverted U-shaped pipe or fitting 26 (Figure 5) having a similarly 60 shaped passage connected at opposite ends with the pipes 22 and 17 which together with the siphon breaker form the water inlet supply line. At the top of the fitting 26 is a pipe connection 27 from which extends a vent 65 pipe or tube 28 forwardly into the upper

part of the radiator and terminating in an upturned end 28a extending into the filling neck 4a of the radiator and above the high water level therein. Extending inwardly from vent pipe connection 27 is a cavity 29 tangential with the top of the U-passage in the fitting, and mounted in this cavity is an extension 30 of the vent pipe 28, having its end terminating beyond the vertical center line of the U-shaped passage. Moreover, 75 the inner end of the vent pipe extension 30 opens in the general direction in which the water flows through the fitting 26, namely, upward in pipe 22 and downwardly in pipe 27, as indicated by the arrows in Figure 5. 80 The purpose of the extension 30 of the vent pipe is to facilitate the breaking of the siphon with as little discharge of water as possible into the radiator, this being due to the fact that the extension is not only reduced somewhat in size, but its inlet opens in the same direction as the water is flowing, and hence less quantity of water will be diverted than would be the case if the extension were omitted. In other words, the arrangement 85 disclosed serves to reduce the flow of water through the vent pipe 28, although no particular disadvantage would result from a more voluminous flow. The necessity for a siphon breaker will be readily understood 90 from the following description of the action of the conditioning device:

In the first place, it is manifest that the suction of the motor when in operation draws large quantities of air into the carburetor for 100 mixture with the liquid hydrocarbon, in accordance with the well known principle of carburetion. Thus the air entering the carburetor is first drawn through the casing 6 and thence to the carburetor through the connecting elbow 7. The air inlet to the casing 6 is through the several radial tubes 14 to the interior of the inner shell 9, and thence in a downward direction toward the bottom of the outer shell, as indicated by arrows in 110 Figure 2. The air thus drawn in contains varying amounts of dust and particles of dirt, depending on the season and the condition of the road. It follows, therefore, that the streams of dust-laden air entering horizontally from all directions, meet each other at the top of the inner shells and then travel vertically downward toward the bottom of the center shell where the air makes a reverse turn through 90° travelling upwardly 120 in the space between the inner and outer casings, and thence discharged through the outlet opening 12 at the top and into the carburetor through the elbow 7.

The dust particles are carried along with 125 the air, but owing to the change in direction on entering the inner shell and the swirling action attending the meeting of the several incoming streams their velocity is reduced somewhat, so that on reaching the end 130

of their downward travel they either drop or their inertia carries them into contact with the surface of the water in the basin and are trapped thereby, the air being thus separated from the dirt passing on and upwardly to the carburetor in relatively clean condition.

The water which is fed to and carried from the basin at the bottom of the outer shell 8 is relatively shallow and stands at a level, which can be varied to meet the desired operating conditions. While the motor is operating the water is being constantly circulated through the basin by the described connections with the cooling system. The water is maintained at a predetermined level by the position of the discharge pipe outlet and the rate of this charge therethrough, it being observed that the outlet pipe 19 is of slightly greater diameter than the inlet pipe 16, so that the rate of discharge is always greater than the rate of intake, and that the level of the opening to the outlet pipe determines the level of the water in the basin. Hence by properly proportioning the inlet and outlet connections and locating the opening to the discharge pipe at the desired height, the proper level for most effective cleaning action is obtained. In general, the higher the water level the greater the effectiveness of the cleaning action within certain limits. For instance, if the level of the water is varied between bottom and top of the conical basin, there will be a marked variation in the area of water exposed. On the other hand, if the level is raised above the top of the conical basin, the passage for the air will be restricted in greater or less degree with the result that the velocity of the air in negotiating the 180° turn may be increased to such a point that the water is agitated and too large an amount is picked up and carried into the carburetor. Hence, it is important to determine the proper water level, which as before suggested, should be somewhere adjacent the top of the conical basin. The air striking the surface of the water manifestly absorbs some moisture which is quite beneficial to efficient carburetion, and therefore is an advantage, but the amount of water so absorbed should not be excessive, as it would result in an undue drain on the cooling water, whereas a normal absorption would not be objectionable from this standpoint.

It also follows that the dirt and dust trapped in the well is carried into the cooling system, and eventually disposed of when the cooling system is drained, as it is or should be periodically under any conditions. This introduction of dirt into the cooling water may at first appear to be impractical, but bearing in mind that the actual amount of dirt collected is small in comparison with the amount of rust particles and other foreign matter which is thrown off under ordinary operating conditions, the added matter is of little consequence.

The flow of water from the cooling system through the intake line to the casing 6, is due to the pressure of the pump 5 which carries the water over the siphon breaker 23 and then downwardly into the basin. So long as the motor is running and the cooling water is under forced circulation, the water continues to flow to and from the casing, and likewise to be discharged, since the pump 24 is operating to withdraw and return it to the cooling system. When the motor stops, the discharge ceases, but in the absence of means for breaking the siphon, the water would continue to flow into the basin, inasmuch as the inlet to the basin is lower than the point of take-off from the cooling system. Hence, by locating the siphon breaker at the high water level and venting it into the top of the radiator, the flow is interrupted as soon as the motor stops by the breaking of the siphon action.

The advantage of the air conditioning apparatus herein disclosed, is the combined use of water and the reversal of the direction of the air through the casing to separate out the particles of dirt. The larger and heavier particles would probably be thrown down into the bottom of the casing and collected without the presence of water, while the finer particles would tend to be carried along with the air currents. Hence the water acts to trap the finer dust particles which otherwise would not be removed. Moreover, the heat from the motor and of the water being circulated through the apparatus, raises the temperature of the walls of the casing with which the air comes into contact, thus pre-heating the air. And finally, the moisture or vapor being constantly given off from the surface of the water, is absorbed by the air and thus improves its condition for more efficient carburetion.

If desired, valves could be installed in the water feed lines so that the water circulation could be shut off in extreme cold weather or during the winter months when dust is not so prevalent as in the dry summer months. Under such conditions, the apparatus would still remove the larger particles of foreign matter, aside from heating the air to some extent, inasmuch as considerable heat would be transmitted to the casing from the motor by conduction.

Having set forth a preferred embodiment of my invention,

I claim:

1. In an air conditioning device for internal combustion motors, the combination with the cooling system thereof, of a casing mounted adjacent said motor and having an air outlet connected with the carburetor of said motor, an air inlet communicating with the atmosphere, and a basin at the bottom

thereof adapted to contain a predetermined level of water, means within said casing for directing the incoming air downwardly over the surface of said water and thence to said air outlet, a water inlet pipe leading from said cooling system to the casing, a water discharge pipe leading from said casing to said cooling system, a pump located in said discharge pipe, and means in said inlet pipe for interrupting the siphon action when said motor is stopped.

2. In an air conditioning device for internal combustion motors, the combination with the cooling system thereof, of a cylindric casing mounted in vertical position adjacent said motor and having an air outlet connected with the carburetor of said motor and an air inlet communicating with the atmosphere, the bottom of said casing being closed to form a relatively shallow basin adapted to contain a predetermined level of water therein, means above said basin for directing the incoming air downwardly over the surface of said water and thence upwardly to said air outlet, a water inlet pipe leading from said cooling system to the casing, a water discharge pipe leading from said casing to said cooling system, a pump located in said discharge pipe and a siphon breaker located in said inlet pipe substantially at the normal water level in said cooling system.

3. In an air conditioning device for internal combustion motors, the combination with the cooling system thereof, of a cylindric casing having an air outlet at its top connected with the carburetor of said motor and air inlet to the atmosphere, the bottom of said casing forming a relatively shallow basin adapted to have a predetermined level of water maintained therein means for conducting the air through said casing and in contact with the surface of said water, an inlet pipe connecting the casing with the cooling system at a level above the level of the water in said casing, and having an inverted U-bend intermediate its ends substantially at the high water level in said cooling system, means for venting said inlet pipe at said U-bend, and a return pipe leading from said casing to said cooling system.

4. In an air conditioning device for internal combustion motors, the combination with the cooling system thereof, of a cylindric casing having an outlet connected with the carburetor of said motor and an air inlet to the atmosphere, the bottom of said casing forming a relatively shallow basin adapted to have a predetermined level of water maintained therein, means for conducting the air through said casing in contact with the surface of the water therein, an inlet pipe connecting said cooling system with said casing and having an inverted U-bend substantially at the high water level of said cooling system, and a vent pipe communicating with the top

of said U-bend and terminating in the radiator of said cooling system above the normal water level therein.

5. In an air conditioning device for internal combustion motors, the combination with the cooling system thereof, of a cylindric casing having an outlet connected with the carburetor of said motor and an air inlet to the atmosphere, the bottom of said casing forming a relatively shallow basin adapted to have a predetermined level of water maintained therein, a cylindric shell mounted in said casing above the basin thereof, closed at its upper end and open at its lower end, a plurality of radial tubes extending from the upper end of said shell through said casing and communicating with the atmosphere, and means for circulating water from said cooling system through said basin and maintaining the same at a predetermined level.

6. In an air conditioning device for the purpose described, the combination with the cooling system and radiator of an internal combustion motor, of a casing having an air outlet communicating with the carburetor of said motor, an air inlet communicating with the atmosphere, water inlet and discharge pipes leading to and from said cooling system and communicating with said casing, means for maintaining the circulation of water through said casing while said motor is in operation, and means for interrupting the circulation when said motor is stopped, comprising vertical up and down branch pipes in said water inlet pipe terminating in an inverted U-bend adjacent the top of said radiator, and a vent pipe extending horizontally from said U-bend and opening into said radiator above the normal water level therein.

7. In an air conditioning device for the purpose described, the combination with the cooling system and radiator of an internal combustion motor, of a casing having an air outlet communicating with the carburetor of said motor, an air inlet communicating with the atmosphere, water inlet and discharge pipes leading to and from said cooling system and communicating with said casing, and a siphon breaker in said water inlet pipe comprising vertical up and down branches terminating in a U-bend at the normal high water level in said cooling system, and a vent pipe extending laterally from said U-bend and terminating in the top of said radiator and having an extension within said U-bend and opening toward the down branch of said siphon breaker.

8. In an air conditioning device for internal combustion motors, the combination with the cooling system thereof, of a casing mounted adjacent said motor in vertical position and having an air outlet connected with the carburetor of said motor and an air inlet communicating with the atmosphere, a water inlet pipe leading from said cooling system

to the casing, and having an inverted U-bend therein at substantially the normal level of the water, a vent pipe extending from said U-bend and terminating above said water level, said vent pipe having an extension within said U-bend opening in the direction of flow of the water therethrough, and a return pipe leading from said casing to said cooling system.
